UNITED STATES PATENT OFFICE.

GEORGE S. TIFFANY, OF NEW YORK, N. Y., ASSIGNOR TO THE GRAY
NATIONAL TELAUTOGRAPH COMPANY, OF SAME PLACE.

TELAUTOGRAPH.

SPECIFICATION forming part of Letters Patent No. 672,631, dated April 23, 1901.

Application filed November 22, 1900. Serial No. 37,342. (No model.)

To all whom it may concern:

Be it known that I, GEORGE S. TIFFANY, a citizen of the United States, residing at New York city, county of Kings, and State of New York, have invented certain new and useful Improvements in Telautographs, fully described and represented in the following specification and the accompanying drawings, forming a part of the same.

10 This invention relates to telautographs or writing-telegraphs of the general class for which patents have heretofore been granted to Elisha Gray and to myself.

The invention relates especially to the provision of means whereby when the sender has finished sending a message an alarm will automatically be sounded until the main switch is moved to throw the transmitting instrument out of circuit.

20 A full understanding of the invention can best be given by a detailed description in connection with drawings showing a preferred construction embodying the same, and such a description will now be given in connection with the accompanying drawings, in which—

Figure 1 is a broken plan view of a transmitting instrument constructed in accordance with the invention. Figs. 2 and 3 are detail views, on an enlarged scale, showing one of the pen-arm supports and connections, looking in the direction of the arrows 2 and 3, respectively, of Fig. 1. Fig. 4 is an enlarged detail showing the connections of the two pen-arms and pen. Fig. 5 is a detail looking in the direction of the arrow 5 of Fig. 4. Figs. 6 and 7 are detail views, taken on the line 6 7 of Fig. 4, showing the parts in different positions. Fig. 8 is a diagrammatic view showing the alarm-circuit connections. 30 Fig. 9 is a view similar to Fig. 8, partly broken away and showing a modification.

Referring to the drawings, A represents the writing-plate on which the paper rests; B, the hand or arm rest; C, the transmitting pen or pencil, and D and E the two pen-arms. The adjacent ends of the pen-arms are connected together, and the pencil is connected thereto near its point by a swivel connection, and the pen-arms are connected to pen-40 drums 10 by means of cords 11, passing around

the pen-drums, and are supported by means of slotted guides 12, all as usual.

The connection between the ends of the pen-arms is formed so that when the pen is in the position of rest a member carried by one arm 55 will be in electrical contact with a member carried by the other arm; but when the pen is moved into writing position these two members will be moved out of contact with each other. This result may be secured in any 60 suitable manner, but, as shown, one of the arms E is provided with a non-conducting sleeve 15 and the arms are secured together by means of a strap 16 of conducting material carried by the other arm D and extending 65 about the sleeve 15. The strap 16 is provided with a lug or shoulder 17, in position to be engaged by a yoke 18, carried by the arm E, and which forms a part of the swivel connection between the arm E and the pen. The lug 17 70 is so positioned that it will be engaged by the yoke 18, as shown in Fig. 7, when the pen is in the position of rest or lying on the arm-rest B, as shown in Fig. 1. When the pen is raised for writing, however, the yoke 18 will be turned 75 away from the lug 17, as shown in Fig. 6, so as to break the electrical connection between them. The strap 16 and yoke 18 are in electrical connection with the brackets 20, and this connection is preferably through the pen-80 arms D E, a good electrical connection between the pen-arms and the brackets being preferably secured by means of a pair of spring-rods 21, adapted to bear on either side of the pen-arm. 85

Referring to Fig. 8, the complete alarm-circuit is as follows: starting from a local battery G, by wire a to a contact-plate b of the master-switch H, contact-spring c, wire d, to connecting-springs 21, then through the pen-arms E and D to the other connecting-springs 21, and thence by wire e through a buzzer I and back to the battery. 90

When the master-switch is in transmitting position, the contact-spring c will be in contact with the plate b; but the circuit will be broken between the lug 17 and yoke 18 when the pen is in position for writing. When, however, the pen is dropped to its position of rest, the lug 17 and yoke 18 will be brought 95 100

into contact and the alarm-circuit will be completed, and the alarm will consequently sound until the master-switch is moved to throw the transmitting instrument out of circuit, by which movement contact between the spring *c* and contact *b* will be destroyed and the alarm-circuit opened.

It will be understood that the invention is not limited to the exact construction or arrangement of the parts or circuit as shown in the drawings, but that changes therein may be made within the claims. For example, instead of running the circuit through the two pen-arms, it might be through one of the pen-arms, as *E*, and through the pen. In this case the wire *e* might be in connection with a suitable bar or rib of conducting material, as shown in Fig. 9, with which rib *g* the pen-handle would contact when in its position of rest, the pen-handle in this case being of conducting material.

What I claim is—

1. The combination with a telegraphic transmitting instrument having a transmitting-pen, of an alarm-circuit, and means whereby break in the alarm-circuit is closed when the transmitting-pen is in the position of rest, substantially as described.

2. The combination with a telegraphic transmitting instrument having a transmitting-pen, of an alarm-circuit, and means whereby said circuit is closed only when the master-switch is in transmitting position and the transmitting-pen in the position of rest, substantially as described.

3. The combination with a telautographic transmitting instrument having a transmitting-pen and pen-arms substantially as described, of an alarm-circuit including a contact member carried by one of the pen-arms and a contact member controlled by the master-switch, and means whereby the circuit is closed through the contact member carried by the pen-arm when the transmitting-pen is in the position of rest, substantially as described.

4. The combination with a telautographic transmitting instrument having a transmit-

ting-pen and pen-arms substantially as described, of an alarm-circuit including the pen-arms, and means whereby said circuit is closed only when the master-switch is in transmitting position and the transmitting-pen is in the position of rest, substantially as described.

5. The combination with a telautographic transmitting instrument having a transmitting-pen and pen-arms substantially as described, and devices for connecting the ends of the pen-arms and the pen including two contact members which are in contact when the pen is in the position of rest and are not in contact when the pen is in the position for writing, and an alarm-circuit including said contact members, substantially as described.

6. The combination with a telautographic transmitting instrument having a transmitting-pen and pen-arms substantially as described; of devices for connecting the ends of the pen-arms including the swiveled yoke 70 18 to which the pen is connected and the insulating-sleeve 15 carried by one of the pen-arms, and the strap 16 carried by the other pen-arm and extending about the sleeve 15, said yoke and strap being formed to engage 75 each other when the pen is in the position of rest; and an alarm-circuit including said yoke and strap, substantially as described.

7. The combination with a telautographic transmitting instrument having a transmitting-pen and pen-arms, of an alarm-circuit including one of the pen-arms, and a spring-contact 21 bearing on said pen-arm substantially as described.

8. The combination with a pen-arm of a te- 85 lautographic transmitting instrument mounted to be capable of a sliding and swinging movement, of a stationary spring-contact 21 bearing on the pen-arm, substantially as described.

In testimony whereof I have hereunto set my hand in the presence of two witnesses.

GEORGE S. TIFFANY.
